UNITED STATES PATENT OFFICE.

FRED B. WARING, OF KANSAS CITY, MISSOURI, ASSIGNOR TO THE OIL WELL HEATING COMPANY, A CORPORATION OF ARIZONA.

PROCESS AND APPARATUS FOR STIMULATING THE PRODUCTION OF OIL.

1,291,302.

Specification of Letters Patent.

Patented Jan. 14, 1919.

Application filed March 18, 1918. Serial No. 223,104.

To all whom it may concern:

Be it known that I, FRED B. WARING, a citizen of the United States of America, residing at Kansas City, in the county of Jackson and State of Missouri, have invented certain new and useful Improvements in the Processes and Apparatus for Stimulating the Production of Oil, of which the following is a specification.

10 Crude oil as found in driven wells in an oil producing field, and liberated from the oil bearing sand or rock is proportionately accompanied by paraffin or asphaltum, the native bitumen which in combination with 15 the crude oil flows into the well, and is pumped out and distilled from the crude oil. The paraffin or the asphaltum, after a period of time accumulates in the oil sand or rock, and clogs the pores of the oil sand strata, 20 and retards the entry of the oil into the well, and its production is curtailed, and finally, a well which has produced oil in paying quantities, fails altogether to respond to the suction of the pump, and is abandoned 25 as a "dry well."

To overcome the resistance of the paraffin, and permit the oil to flow after its cessation, it has been attempted to heat the oil in the well, by various processes, and endeavor to 30 liquefy the resisting substances, with the result that the heat fails to penetrate the oil sand, so as to liquefy these substances therein, and the degrees of heat are confined to the immediate body of oil in the well.

35 It is the purpose of my invention to create a heated zone, extending into the oil bearing sand or rock at a liquefying temperature and co-extensive with the body of oil in the oil bearing rock, hence a yield of 40 the oil for a determinate period of time is assured, with an average daily production of the oil, thus opening up the clogged pores in the oil-bearing rock, for the unobstructed flow of the oil.

45 In order to maintain a heated zone in the oil sand rock, it is the purpose of the invention to locate an electric heating apparatus on the pumping conduit between the perforated pipe for the oil and the working 50 barrel through which the oil is pumped, and maintaining a high amperage of heat, distributed directly to the oil bearing sand, the apparatus employed and the procedure being shown in the illustrations in the accom-

panying drawing, forming a part of this specification, in which—

Figure 1. is a view, in vertical section, of an oil well, showing the lower end of the casing at the entrance to the oil bearing rock or sand; also showing the protected heater within the oil sand, and the perforate pipe through which an exhaust of the oil is made through the heater, the heater being connected with the pump barrel and tubing, the heater being connected electrically with the armored circuit.

Fig. 2. is a view of the heater and hollow insulated core, and portions of the heating coils and protector for creating a heating zone with oil elimination, in section.

Fig. 3. is a sectional view through the heater, taken on line 3, 3, in Fig. 2. With tube or pipe 5, which extends downwardly from the surface of the ground, within the casing 6, is connected by collar 7, the upper 75 end of the pump barrel 8. With the lower end of the pump barrel is connected by the collar 9 a pipe 10. The core of the heater is formed by a tube 12, of the same circumference as the tube 10.

80 Insulators, of high electric resistance, such as porcelain tubes 13, extend around the circumference of the core 12, the insulators, as shown, being short in length, and provided with interfitting joints 14. The insulating 85 tubes are held in position on the core 12, by a lock-nut 15, near the upper end of the core, and by a lock-nut 16, near the lower end of the core. Between the porcelain insulators or tubes 13 and core 12 is a bedding 17, 90 composed of insulating material.

The heating or resistance coils 18 are in sections, one coil being connected with another by an overlap joint 19.

95 The protector for the heating coils, when raised and lowered within the oil sand, is formed by a long electrical casing 20, extending around the series of heating coils, so as to leave a space 21 between the coils and the inner surface of the casing. The 100 case 20 is provided with perforations 22, arranged short distances apart, between the upper and lower ends of the case. At the upper end of the case is a cap 23, provided with a downwardly-extended annular flange 105 24, which fits within the upper end of the case. Extending upwardly from the upper portion of the cap 23 is an internally screw-

threaded collar 25. The adjacent ends of the respective tubes 10 and 12 are also screw-threaded, and are united by the collar 25. Supporting the lower end of the case 20 is a 5 cap 26, having a flange 27, and an internally screw-threaded collar 28. The lower end of the tube 12 is also screw-threaded, and with the collar 28, which is secured to said end of the tube 12, is connected the screw-threaded 10 upper end of the perforated pipe 30. An anchor, or short pipe 31, is connected by the collar 32 with the lower end of the perforated pipe 30, the lower end of pipe 31 having a collar 33, closed by a plug 34. The 15 cap 26 is provided with ducts 35, for the leakage of any oil entering the casing 20 through the perforations 21, from seepage from the oil sand. An electric conductor 36 is connected with an electric generator 37, 20 and leads through an opening 38, in the cap 23, and is connected with the upper terminal of one of the sectional resistance coils 18, at the upper end of the heater. The lower terminal of the lower coil is connected by a conductor 39, with the casing 20, 25 the return circuit being through the casing 20 and the oil pumping tubes.

The insulated conducting wire 36 is in short lengths, each length being inclosed 30 within a conduit or insulated pipe 40, the sections of the pipe being connected with each other by a joint 41, the sections of pipe being held in position upon the side of the tubing by the clamp 43.

35 At a point on the pump tubing above the working barrel is a damper 44, which retards the generated heat within the oil-producing strata, until its effectiveness is spent when it rises through the metal casing of 40 the well, to the surface of the ground.

The oil in the well is first exhausted by the pump, to a point corresponding in height to the topmost perforation in the perforated pipe 30, before the current from the generator 37 is admitted to the heater. An electric current from the generator is then caused 45 to energize the coils 18, and during which time the operation of the pump is continued, to hold the oil and water below the point of the electrical contact from the resistance material attached to the protecting case 20, because a ground is established at that point, otherwise the rising of the liquid to a point in which the heater was submerged, the current would pass through the liquid, instead of through the higher resistance, heat-imparting material, and cause a short circuit.

60 The procedure, therefore, is to treat the oil-bearing sand in an oil well with dry heat, to liquefy the obstructions in the pores, draw the oil through the heater and hold the heat radiated from the heater from escaping from the well, and in creating a heat zone 65 through the oil bearing rock. The wells

thus treated will, after the removal of the obstructions continue for several months, to respond to the pump action, and furnish an average daily supply of oil, before a re-heating is necessary. Heretofore, in stimulating 70 the production of oil in oil wells, heaters have been employed, all of which have failed to be operative because all have been tightly closed in a protecting case or jacket. This failure is due to nature placing moisture 75 within the air-tight case or jacket, in the form of sweat, which can not be insulated against, therefore, upon generating an internal heat, this moisture becomes vaporized to a high pressure, sufficient at least to open 80 up a vent within the protecting case, and is followed by an exhaustion to a point less than the hydrostatic pressure of the fluid in the well. This partial vacuum induced is followed by an inrush of water or oil, or a 85 mixture of both, which produces a short circuit within the protecting case, thus placing the apparatus out of operative condition. There is no way that this internal pressure can be dissipated, and patents covering 90 electric heaters for this purpose have all followed the same inclosed type idea of which the Patent No. 785554, dated March 7, 1905, granted to applicant, is an illustration, all having failed to produce the desired results, being unable to overcome the 95 laws of nature in the matter of eliminating the internal moisture, of which there is no known way.

With a practical experience, covering a 100 number of years by applicant in the oil field, the above facts were clearly determined, and the idea of an open type heater presented itself. With the openings or perforations in the protecting case allowing the 105 electrical resistance, terminals, etc., to become wet on lowering the heater into the well, the fluid is pumped out or exhausted, the pump continuing to operate during the heating period, so as to continue to discharge the fluid from the well as it fills in (a little at a time), the fluid being held below the heater, at all times during the heat treatment, and what little fluid there is on the electrical resistance and within the open 110 or perforated protecting jacket, is vaporized by the passing of a low current through the resistance, completely drying out all moisture within said jacket. In other words, this open type heater readily offers 115 means of dissipating the vapor arising from the generated heat within, by means of the openings in the protecting jacket, through which the direct rays of unconfined dry heat are imparted to the residuum lining the wall of the well. Such residuum gathers on and in the pores and fissures of the oil-bearing strata, producing sufficient resistance to the incoming fluid to hold it from 120 entering the well.

In other well-known processes, the employment of heat has been for the purpose of vaporizing the water or gasifying oil, to a sufficient pressure upon the fluid in the well 5 to force the oil to the surface of the ground. No application, heretofore, of the unconfined, direct rays of dry heat to the oil-bearing strata, having been described or claimed.

Having fully described my invention, 10 what I now claim as new and desire to secure by Letters Patent is:

1. The herein described process of stimulating the production of oil, which consists in creating within the oil-bearing strata and 15 its obstructions an increasing degree of direct rays of unconfined dry heat, bearing directly upon the residuum lining of the well, sufficient to liquefy paraffin or other obstructions to the incoming oil of the oil- 20 bearing strata.

2. The herein described process of stimulating the production of oil, which consists, first, in exhausting the liquid in the well, heating the oil-bearing material with the application of the direct rays of unconfined 25 dry heat, and simultaneously retarding the heated temperature.

3. The herein described process of stimulating the production of oil, which consists 30 in exposing the oil-bearing material to the

direct rays of unconfined dry heat, and liquefying the obstructions and retarding the heat in its escape from the well, and removing simultaneously the liquid seepage from the oil-bearing material.

35

4. The herein described process of stimulating the production of oil, which consists in exposing the oil-bearing strata to the direct rays of unconfined dry heat, with a gradual increase in the degree of temperature of the zone of heated oil-bearing material, until the residuum has been removed.

5. In an apparatus for the stimulation of the flow of oil in oil wells, a heater, and a protecting exterior perforated case or shell 40 upon the heater.

6. In an apparatus for the stimulation of the flow of oil, a heater, and a protecting exterior perforated case or shell, having oil-draining ducts.

7. In an apparatus for the stimulation of the flow of oil, a heater, and a protecting exterior perforated case having heads supported by the heater, and ducts in one of said heads for draining the oil from the 55 casing.
